(57) **CLAIM**

The ornamental design of a flexible cellular phone holder, as shown and described.

DESCRIPTION

FIG. 1 is a perspective view of the flexible cellular phone holder holding a cellular phone of the new design;

FIG. 2 is a front elevation view of the flexible cellular phone holder holding a cellular phone thereof;

FIG. 3 is a perspective view of the flexible cellular phone holder with hands open;

FIG. 4 is a perspective view of the flexible cellular phone holder with hands closed;

FIG. 5 is a front elevation view of the flexible cellular phone with hands open thereof;

FIG. 6 is a rear elevation view of the flexible cellular phone with hands open thereof;

FIG. 7 is a side elevation view of the flexible cellular phone with hands open thereof;

FIG. 8 is a side elevation view of the flexible cellular phone with hands closed thereof;

FIG. 9 is a top plan view of the flexible cellular phone with hands open thereof;

FIG. 10 is a top plan view of the flexible cellular phone with hands closed thereof;

FIG. 11 is a front elevation view of the flexible cellular phone with hands closed thereof; and,

FIG. 12 is a rear elevation view of the flexible cellular phone with hands closed thereof.

The broken line showing of a cellular phone in FIG. 1 and FIG. 2 is for illustrative purposes only and forms no part of the claimed design.

UNITED STATES PATENT AND TRADEMARK OFFICE
CERTIFICATE OF CORRECTION

PATENT NO. : D669,462 S
APPLICATION NO. : 29/410128
DATED : October 23, 2012
INVENTOR(S) : Lior Avrahami and Simha Dan

Page 1 of 1

It is certified that error appears in the above-identified patent and that said Letters Patent is hereby corrected as shown below:

Title Page, item (73);

The Assignee is incorrectly listed on the on the patent as Funuy Rico, Inc., while both the original application and the form PTOL-85 lists the Name of the Assignee as Funky Rico, Inc. with a "k" not a "u".

Signed and Sealed this
Twenty-sixth Day of March, 2013

Teresa Stanek Rea
Acting Director of the United States Patent and Trademark Office
